2,911,800

ROOM AIR CONDITIONER CONDENSATE SUMP Stephen L. McMillan, Jeffersontown, Ky., assignor to
General Electric Company, a corporation of New York

Application October 27, 1958, Serial No. 769,652

4 Claims. (Cl. 62—280)

The present invention relates to a room air conditioner and more particularly to a condensate water drain arrangement for the sump of such air conditioner which at some time might be exposed to freezing weather conditions.

Air conditioners of the self contained type usually comprise a casing or housing having a partition or barrier dividing the casing into inner and outer compartments, the inner compartment intended to be located in an enclosure (room) and the outer compartment outside the room. These units employ a refrigerating apparatus including at least two heat exchangers, one located within the inner compartment and the other located in the outer compartment which is exposed to the outdoor air. Fans are provided in the compartments for circulating air through the respective compartments and over the heat exchangers mounted within them. In a typical arrangement, the fans are mounted on a common drive shaft extending through the partition and driven by an electric motor which is usually mounted on the partition. Some of these air conditioners employ a refrigeration system of the reversible type having heat exchangers which are interchangeably operable either as a condenser or an evaporator to both heat and cool the enclosure. The apparatus is provided with a sump located beneath the heat exchanger in the outer compartment and means are provided for collecting condensate water from either of the heat exchangers and delivering the water to the sump in the outer compartment. In order to dispose of the condensate water collecting within the sump, many conditioners provide a slinger ring attached to and surrounding the periphery of the outdoor fan. The slinger ring extends or dips into the condensate water in the sump and, during rotation throws the water out of the sump onto the outside heat exchanger where it is either evaporated into the air stream or carried in small droplets by the air stream out of the unit.

During the winter months, when using this type of slinger ring, there is a possibility that it might become solidly frozen within the condensate water if the outside temperature drops below freezing. If the condensate water in the sump freezes around the slinger, then when the conditioner is turned on, the fan cannot rotate, and this causes the fan motor to overheat or results in some other serious damage to the mechanical parts of the unit. Means must be provided, therefore, to eliminate the danger of ice forming around the slinger ring when the outdoor temperature drops below freezing.

Accordingly it is an object of the present invention to provide an improved condensate water drain arrangement for disposing of the condensate water which collects in the sump of an air conditioning unit when the outdoor temperature approaches the freezing point of water.

Further objects and advantages of the invention will become apparent as the following description proceeds and the features of novelty which characterize the invention will be pointed out with particularity in the claims annexed to and forming a part of this specification.

2

In carrying out the present invention there is provided an air conditioning apparatus having a compressor and a pair of heat exchangers, one of which is mounted in a compartment exposed to indoor air and the other being mounted in a compartment exposed to outdoor air. A condensate sump is provided beneath the outdoor heat exchanger and means are provided for conducting condensate water forming on either of the heat exchangers to the condensate sump. In order to dispose of the condensate water in the condensate sump when the outdoor temperature drops below a predetermined temperature, there is provided a drain means in the bottom of the sump comprising a thermally responsive disk having a drain hole centrally located on the disk. The outer edge of the disk is mounted in water tight sealed relation with the edges of an opening in the bottom of the sump. When the outside temperature is above a predetermined temperature the disk is flexed so that its central portions are flexed in the upward direction so that the drain hole is maintained a distance above the bottom of the sump thereby preventing the water from flowing through the drain hole. When the outdoor temperature falls below a predetermined temperature the disk flexes downwardly to a concave position so that the drain hole of the disk is below the level of the bottom of the sump for draining the condensate water out of the sump.

For a better understanding of the invention reference may be had to the accompanying drawing in which:

Fig. 1 is a vertical side view in section of an air conditioning apparatus incorporating the present invention;

Figs. 2 is a fragmentary enlarged elevation view, partially in section, showing the improved drain arrangement.

Referring now to Fig. 1 there is shown an air conditioner of the reversible refrigerant flow type which is arranged to be positioned within an opening in an enclosure. The unit comprises a casing 2 which is divided by a barrier 3 into an inner compartment 4, within which an indoor heat exchanger or evaporator 6 is mounted, and an outer compartment 7, containing an outdoor heat exchanger or condenser 8. The heat exchangers 6 and 8 are connected in refrigerant flow relationship with a compressor 9 also positioned in the outer compartment 7. The conditioner is provided with a reversing valve 11 which may be selectively operated to reverse the flow of refrigerant to the heat exchanger units 6 and 8. When the conditioner is on the cooling cycle, air is drawn from within the room by an air moving means or fan 12 and passed over the heat exchanger 6 which is operated as an evaporator. During operation of the unit on a cooling cycle, the moisture from the room air condenses onto the coil surfaces of the heat exchanger and drains downwardly where it is collected in a suitable drip tray 13. The condensate water is delivered from the drip tray 13 by means of an insulated conduit 14 to a condensate collection sump 16 formed in the base of the unit in the outer compartment 7 of the conditioner.

As shown in Fig. 1, an air moving means or fan 17 is disposed in the outer compartment and is driven by a shaft 18 from a motor 19 mounted in the barrier 3. When the unit is on the cooling cycle, the fan 17 circulates outside air over the heat exchanger 8 to remove the heat from this heat exchanger, which is operating as a condenser. More specifically, the fan 17 pulls outside air through the inlet opening 20, blowing it inwardly against the barrier 3 whereupon it flows upwardly through the heat exchanger 8 and is then discharged through the outlet opening 21. When the unit is operating on the heating cycle, the reversing valve 11 reverses

the flow of refrigerant to the heat exchangers 6 and 8 thereupon utilizing the heat exchanger 6 as a condenser and heat exchanger 8 as an evaporator. During

the heating cycle, air from within the room is blown by the fan 12 over the heat exchanger 6 whereupon it is warmed and discharged back into the room. Outside air is blown over the heat exchanger 8, which acts as an evaporator, to absorb heat from this air. The heat removed from the outdoor air by the evaporator is transferred by the refrigerant flowing through the system to the condenser where it warms the air from the room. The outer compartment heat exchanger 8 condenses moisture out of the air during the heating cycle and this moisture also collects in the condensate collection sump 16.

Mounted on the extremities of the fan 17 is a slinger ring 22 which extends downwardly into the space defined by the sump 16 and is at least partially submerged in the condensate water collected therein. As the fan rotates, water is picked up by the slinger ring and thrown by centrifugal force onto other parts of the outdoor compartment and, more specifically onto the heat exchanger 8. During the cooling cycle when the heat exchanger 8 is acting as a condenser, the condensate water thrown onto this heat exchanger vaporizes and cools the heat exchanger thereby increasing its capacity and the capacity of the refrigeration system as a whole.

As thus far described, this air conditioner with its reversible heat exchanger system forms no part of the present invention, but is intended only to be illustrative of one type of air conditioner to which this invention is particularly well adapted. It is not intended to limit the invention only to air conditioners of the reversible refrigerant flow type, as the invention is also very useful in the ordinary type of air conditioner which may be permanently mounted in the wall of a room and used during the cooler months of the year to provide ventilation or to exhaust air from the room. As will now be described, the invention deals with a means for draining condensate water from the sump when the outdoor temperature drops below a predetermined temperature.

In order to dispose of the condensate water in the condensate sump 16 the present invention provides a drain means which operates to drain the water out of the sump whenever the outdoor temperature approaches the freezing point of water. Mounted in the bottom of the sump, is a thermally responsive bimetal disk 24 that occupies the upwardly curved or convex shape, shown in solid lines in Figs. 1 and 2, when the temperature is above a predetermined temperature such as 36° F. The disk occupies the downwardly curved or concave shape, shown in dotted lines in Fig. 2, when the temperature falls below the above mentioned predetermined temperature. The bimetal disk 24 is mounted in an opening in the bottom of the sump and is retained in water tight sealed relationship therein by means of a flexible or resilient gasket 26, which surrounds the entire outer perimeter of the disk 24. The gasket 26, in turn, is connected in sealed relationship to the edge 27 of the opening. The gasket permits the outer perimeter or edge of the bimetal disk to move slightly with respect to the edge 27 of the opening and allows the disk to flex or move from one position to the other during changes in the temperature.

Centrally located on the disk is a drain hole 28 which is held a short distance above the bottom of the sump and above the lowermost edge 22a of the slinger ring 22 when the bimetal disk is flexed in the convex position shown in solid lines in Fig. 2. That is, whenever the temperature is above the predetermined temperature, the disk holds the drain hole above the bottom of the sump and above the edge 22a of the slinger ring. In this manner, whenever the outdoor temperature is above the predetermined temperature (such as 36° F.), the condensate water is maintained at a level in the sump 16 so that it is picked up and slung out of the sump by the slinger ring. Whenever the outdoor temperature falls below the predetermined temperature, the bimetal disk flexes to the dotted line position shown in Fig. 2 and

moves the drain hole 28 below the level of the bottom of the sump thereby causing the condensate water to drain through the hole 28. It should be pointed out that the bimetal disk can be provided which accurately moves 5 between two flexed positions within two or three degrees of any desired temperature. Means (not shown) can be provided beneath the drain hole for carrying the condensate water to any desired location or the unit can be positioned such that the water drains directly onto the 10 ground outside the building.

The drain hole 28 in the disk also acts as an overflow hole whenever conditions are such that an excessive amount of water is condensed out of the air and this 15 maintains the water at a safe level in the sump. It permits the water to overflow and drain to the outside, preventing water from flowing into other portions of the unit or possible overflowing onto the floors of the enclosure.

By the present invention there has been provided a condensate sump drain arrangement for an air conditioning unit which operates to dispose of the condensate water when ever the outside temperature drops below a predetermined level. Moreover the drain is initiated 20 automatically by the lowering of the outdoor temperature and requires no other type of control.

While in accordance with the patent statutes there has been described what is considered to be the preferred embodiment of the invention, it will be obvious to those skilled in the art that various changes and 25 modifications may be made therein without departing from the invention and it is therefore the aim of the appended claims to cover all such changes and modifications that fall within the true spirit and scope of the invention.

35 What I claim as new and desire to secure by Letters Patent of the United States is:

1. In combination with a self-contained air conditioner having a condensate water collection sump exposed to outdoor temperature conditions and including a water 40 slinger extending into the sump, drain means in the bottom of said sump including a thermally responsive disk mounted in an opening in the bottom of said sump with the outer edge of said disk in water tight sealed relation with the edge of the opening, said disk having a drain hole positioned adjacent the central area thereof, said disk 45 being flexed upwardly with respect to the bottom of said sump when the temperature of the outside air is above a predetermined temperature so that said drain hole is maintained above the bottom of said sump to prevent the water from flowing through said drain hole, said disk flexing downwardly with respect to the bottom of said 50 sump when the temperature of the outside air falls below the predetermined temperature so that said drain hole is disposed beneath the level of the bottom of said sump to permit condensate water to drain through said drain hole.

2. In combination with a self-contained air conditioner having a condensate water collection sump exposed to outside temperature conditions and including a rotatable 55 water slinger dipping into said sump, drain means in the bottom of said sump including a thermally responsive disk mounted in an opening in the bottom of said sump, a resilient sealing member attached entirely around the outer perimeter of said disk and connected to the edge of said opening in said sump in water tight sealed relation, said disk having a drain hole positioned approximately in the center thereof, said disk being flexed upwardly with respect to the bottom of said sump when the temperature of the outside air is above a predetermined temperature so that said drain hole is maintained a distance 60 above the bottom of said sump to retain condensate water in said sump, said disk being flexed downwardly with respect to the bottom of said sump when the temperature of the outside air is below said predetermined temperature so that said drain hole is disposed beneath

the level of the bottom of said sump to permit condensate water to drain through said drain hole.

3. In combination with a self-contained air conditioner having a condensate water collection sump exposed to outdoor temperature conditions and including a rotatable water slinger dipping into said sump, drain means in the bottom of said sump comprising a thermally responsive bimetal disk mounted in an opening in the bottom of said sump, a flexible sealing gasket connected between the outer perimeter of said bimetal disk and the inner edges of said opening in the bottom of said sump, said flexible gasket permitting the outer perimeter of said disk to move relative to said inner edge of said opening to allow said bimetal disk to flex according to temperature changes of the outside air, said disk having a drain hole positioned approximately in the center thereof, said disk being flexed upwardly with respect to the bottom of said sump when the temperature of the outside air is above a predetermined temperature thereby maintaining said drain hole a distance above the bottom of the sump and retaining condensate water in said sump, said disk being flexed downwardly with respect to the bottom of said sump when the temperature of the outside air is below a predetermined temperature so that said drain hole is disposed beneath the level of the bottom of said sump to permit condensate water to drain through said drain hole.

4. In combination with a self-contained air conditioner

having a condensate water collection sump exposed to outside temperature conditions and including a rotatable water slinger ring extending into said sump, drain means in the bottom of said sump comprising a thermally responsive disk mounted in an opening in the bottom of said sump with the outer edge of said disk in water tight sealed relation with the bottom of said sump, said disk having a drain hole positioned approximately in the center thereof, said disk being flexed upwardly with respect to the bottom of said sump when the temperature of outside air is above a predetermined temperature so that said drain hole is maintained a distance above the lowest portion of said slinger ring extending into said sump, said disk being flexed downwardly with respect to the bottom of said sump when the temperature of the outside air is below a predetermined temperature so that said drain hole is disposed beneath the level of the bottom of said sump to permit condensate water to drain through said drain hole.
